UNITED STATES PATENT OFFICE.

HUBERT E. VAN NORMAN, OF CHICAGO, ILLINOIS, ASSIGNOR TO AMERICAN DRY MILK INSTITUTE, INC., OF CHICAGO, ILLINOIS, A CORPORATION OF ILLINOIS.

DESIGN FOR AN ANIMAL DISPLAY SIGN.

Application filed September 7, 1928. Serial No. 28,066. Term of patent 7 years.

To all whom it may concern:

Be it known that I, HUBERT E. VAN NORMAN, a citizen of the United States, residing at Chicago, in the county of Cook and State of Illinois, have invented a new, original, and ornamental Design for an Animal Display Sign, of which the following is a specification, reference being had to the accompanying drawing, forming part thereof.

The figure is an elevational view of an animal display sign showing by new design.

I claim:

The ornamental design for an animal display sign, as shown.

HUBERT E. VAN NORMAN.
